UNITED STATES PATENT OFFICE.

WALTER S. MAYER, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

ELECTRIC SWITCHING MECHANISM.

1,322,922.

Specification of Letters Patent. Patented Nov. 25, 1919.

Application filed November 20, 1918. Serial No. 263,244.

To all whom it may concern:

Be it known that I, WALTER S. MAYER, a citizen of the United States, residing in the city of Philadelphia, county of Philadelphia, 5 and State of Pennsylvania, have invented certain Improvements in Electric Switching Mechanism, of which the following is a specification.

My invention relates to switching mechanism adapted for general use but it is designed particularly for controlling electric headlights.

Its object, generally, is to provide sturdy electrical switching mechanism having the minimum tendency to get out of order or 15 20 25

for controlling one or more oppositely disposed headlights, either by cutting them out or dimming them. A special object is to provide improved means disposed, operating and held in a plane parallel to a supporting 30 35 40

base for effecting the switching functions, whether in connection with headlights or otherwise.

Usual applications of the invention are to lights placed at one or both ends of a locomotive in combination with a switch in the locomotive cab by which the engineer controls such lights.

The nature and advantages of the improvement will appear more fully from the following description and the accompanying drawings in illustration of types and applications thereof.

In the drawings, Figure 1 is a plan view of a switch comprised in my improvements, Fig. 2 is an elevation of the same with parts shown in section taken on the line 2—2 of Fig. 1, Fig. 3 is a plan view of a second form 45 50 55

of the switch in modification of that shown in Figs. 1 and 2, Fig. 4 is an elevation showing parts in section taken on the line 4—4 of Fig. 3, Fig. 5 is a plan view of a third form of switch in further modification of that shown in Figs. 1 and 2, Fig. 6 is an elevation 60 65 70

of the structure shown in Fig. 5, Fig. 7 is a diagrammatic view in illustration of an application of the improvements, and Fig. 8 is a diagrammatic view in illustration of a second application of the improvements.

The switch illustrated in Figs. 1 and 2 is a preferred form of the device for certain uses and comprises a base 1 on which is fixed a conducting bearing 2 by the screw 3 and

bolt 4, the bearing having an offset part 2' 55 which stands away from the base. A bifurcated lever 5, comprising the two conducting strips or plates 5' and the insulating handle 5'', is connected in rocking relation to the offset part 2' by the bolt 6, the plates lying 60 on opposite sides of the part 2' and being fulcrumed thereon by the bolt by which tendency to objectionable lateral movement is reduced. A detent 7 and a coiled spring 65 70 75 8 act in a longitudinal socket 5^a in the handle 5'', between the plates 5', which are connected to such handle on opposite sides thereof in insulated relation to the detent and spring.

A segment of bent controlling member 9 70 is fixed to the base 1 by the bolts 10 and 11; the segment being disposed symmetrically with respect to the fulcrum 6, lying between the plates 5' having the median notch 9' for engaging the detent 7, and serving to hold 75 the lever against lateral movement as well as to control its action in its plane of oscillation parallel to the base. Contact members 12 and 13, having the respective offset members 12' and 13', are fixed to the base 1 by the 80 respective screws 14 and 15 and bolts 16 and 17 respectively. Symmetrically with relation to the fulcrum 6, the parts 12' and 13' being adapted for entry alternately between the parts 5' in close frictional or wedging 85 90 95 relation when the lever 5 is swung to the limit of its movements against the ends of the segment 9. The relations of the parts 5' to the parts 12' and 13' are such that good contact is insured since such parts are not liable to the usual tendency of switch members to get out of place by springing or bending away from their correct positions.

Resistance 18 has its ends clamped in the firm conducting bearings 19 and 20 which 95 are fixed to the base 1 by concealed screws 21 and 22, the resistance being held thereby parallel to the base with its ends in proximity to the contacts 12 and 13. Conductors 23 and 24, concealed in and protected by the 100 base, connect the respective bolts or posts 16 and 17 with the screws 23 and 24 and, therethrough, with the bearings 19 and 20 and the opposite ends of the resistance 18.

It will be understood that the posts or 105 bolts 4 and 17 are directly connected through the parts 2, 5' and 13, when the parts 5' and 13' are in contact, and when the parts 5'

engage the part 12' the posts or bolts 4 and 17 are indirectly connected through the parts 2, 5', 12, 16, 23, 21, 19, 18, 20, 22, and 24, the resistance being thrown thereby into the circuit.

When it is desired to hold the circuit open, the lever 5 is thrown to the median position where it is held by the engagement of the detent 7 in the notch 9'.

10 In the modification illustrated in Figs. 3 and 4, the resistance 18 and its connections are omitted. Hence, when the lever 5 is moved to position for engaging the plates 5' with the part 12' of the member 12, direct connection is made between the terminal posts 4 and 16 through the parts 2, 5', and 12; when the lever is moved to position for engaging the plates 5' with the part 13' of the member 13, direct connection is made between the terminal posts 4 and 17 through the parts 2, 5', and 13, and when the lever is in the median position with the detent 7 in engagement with the notch 9' of the segment 9 both circuits are held open.

25 In the modification illustrated in Figs. 5 and 6, an addition is made to the structure shown in Figs. 1 and 2 by fixing to the base a conducting bearing 25 by a screw 26 and a binding post or bolt 27 which is connected 30 by a conductor 28, concealed in the base, with a bolt 4, the bearing 25 having an offset part 25'. A switch lever 29 is connected to the part 25' in rocking relation by the bolt 30 which passes through the lever's bifurcated conducting members 29' disposed on opposite sides of the part 25'. A contact member 30 is connected to the base by the screw 31 and the bolt 32, the member having a part 30' offset from the base so as to enter 40 in close frictional contact between the parts 29' when the lever is thrown to the position illustrated.

A segment 33 is fixed to the base and lies between the members 29', being provided 45 with a notch 33' for engaging the detent 34 carried in the insulating handle 29'' and pressed forward by the spring 35.

The several parts of this auxiliary switch are thus held firmly in correct relation par- 50 allel to the base.

When the lever 29 is in the position illustrated, the posts 4 and 32 are connected through the conductors 28, 27, 25, 29', and 30, the posts 4 and 16 being connected as 55 previously described through the parts 2, 5', and 12 when the lever 5 is in the left hand position. When the lever 29 is thrown to the right, with the detent 34 engaged in the notch 33', the circuit between the posts 60 27 and 32 is held open. The further connections and actions of this mechanism will appear hereafter.

In the operation of the invention as illustrated in Fig. 7, a turbine operated electric 65 generator 35 supplies current to the head

light lamp 36; the auxiliary lamps 37, 37', and 37'', and the cab lamps 38 of a locomotive. Current flows from a generator 35 through the conductor 40 to the lamp 36 and thence through the return conductor 41; 70 from the conductor 40 through the branch conductors 42, 42' and 42'' containing the respective lamps 37, 37' and 37'' to the return conductor 43, and from the conductor 40 through the branch conductor 44 containing 75 the lamps 38 to the return conductor 43. The conductor 41 is connected with the switch member 13 and (through the parts 24, 18, and 23) with the switch member 12. The conductor 43 is connected by the conductor 45 with the bearing 2. When the lever 5 engages the contact 13, the lamp 36, as well as the remaining lamps, receives its normal flow of current and the illumination is of normal brilliancy, 80 but when the lever 5 engages the contact 12 so that the resistance 18 is thrown into circuit, the lamp 36 is dimmed while the remaining lamps burn with normal brilliancy. 85

In the operation of the invention as illustrated in Fig. 8, the generator 35 is connected in circuit with the lamps 36, 37, 37', 37'' and 38 by means of the respective conductors 40, 41, 42, 42', 42'', 43 and 44, with the modifications in the connections of the conductors 41 and 43 for adaptation to the use of a second head light lamp 46 together with the auxiliary lamp 47. Here the conductor 43 is connected by the conductor 45' with the contact member 30, and the latter is connected through the conductor 48, resistance 18 and conductors 49, 2, 28, and 25 to the lever 29. The lamps 46 and 47 are in circuits comprising the conductors 50 and 50', the former connecting the conductor 44 with 100 the member 12, which, like the member 13, is adapted to be connected with the member 2 by the lever 5. 105

In the position of the mechanism shown, the connection of the conductor 41 with the lever 5 is broken, hence, no current flows through the lamp 36, and the current from the conductor 44 flows through the parts 50, 50', 46, 47, 12, 5, 2, 28, 25, 29, 30 and 45' to the conductor 43. All of the lamps excepting 36 are now burning at their normal capacity. When the lever 29 is thrown off the point 30, current from the conductor 50 flows through the parts 12, 5, 2, 49, 18, 48, 30 and 45' to 43, the lamps 46 and 47 being 110 dimmed by thus throwing the resistance 18 into circuit therewith. When the lever 5 is thrown off the point 12, the circuits through the lamps 46 and 47 are broken, and, when the lever is thrown on the point 13, the lever 29 being on the point 30, the conductor 41 is connected with the conductor 43 through the parts 13, 5, 2, 28, 25, 29, 30 and 45' and the normal current flows through the lamps 36, 37, 37', and 37''. When the lever 5 is 115 120 125 130

on the point 13 and the lever 29 is off the point 30, current flows from the conductor 41 through the parts 13, 5, 2, 49, 18, 48, 30 and 45' to the conductor 43, thus throwing 5 the resistance into the circuit of the lamp 36 which is dimmed thereby.

It will be understood that various modifications may be made in the details of the construction without effecting the functions 10 of my device and hence I do not desire to be limited to the specific structure shown and described.

Having described my invention, I claim:

1. In a switching mechanism, the combination with an insulating base, of a conducting member fixed thereto, a conducting lever fulcrumed to said member so as to oscillate parallel to said base, one of said conductors having a bifurcated connection 20 with the other, a contact fixed to said base for engaging said lever in conducting relation, and a segment connected to said base and engaging said lever so as to control its movements.

2. In a switching mechanism, the combination with an insulating base, of a stationary conducting device fixed thereto, an oscillatory bifurcated conducting device fulcrumed to said stationary device so as to 30 act substantially parallel to said base, and a contact device fixed to said base and adapted to be engaged by the bifurcations of said oscillatory device.

3. In a switching mechanism, the combination with an insulating base, of a stationary conducting device fixed thereto, a conducting lever fulcrumed to said stationary device so as to oscillate substantially parallel to said base, a contact device fixed to said 40 base for engagement with said lever, and a segment fixed to said base for controlling the action of said lever, said segment and lever providing connecting means whereby the former prevents the latter from moving 45 laterally to its plane of oscillation in either direction.

4. In a switching mechanism, the combination with an insulating base, of a conducting member fixed thereto and having an offset part, a lever fulcrumed on said member and having connected conducting parts placed on opposite sides of said part first named, and a second conducting member fixed to said base and having an offset part 55 adapted to be engaged between said parts of said lever.

5. In a switching mechanism, the combination of a lever having conducting bifurcations, a conducting member to which 60 an end of said lever is fulcrumed, a contact member adapted for entry in wedging relation between said bifurcations, and a segment adapted for preventing the lateral movement of said lever in either direction.

6. In a switching mechanism, the com-

bination of a conducting member having an offset part, a lever having conducting bifurcations fulcrumed to said member on opposite sides of said part, and contact members having offset parts between which said lever is adapted to oscillate and which are adapted for entry between said bifurcations.

7. In a switching mechanism, the combination of a conducting member, a bifurcated lever fulcrumed on said member, a contact member adapted for entry in wedging relation between said bifurcations and a controlling segment disposed between said bifurcations.

8. In a switching mechanism, the combination of a conducting member, a lever having conducting bifurcations fulcrumed to said member, a contact member adapted for entry in wedging relation between said bifurcations, and a segment disposed between said bifurcations, said segment and lever having co-acting means for holding the latter.

9. In a switching mechanism, the combination with a base, of a conducting member fixed to said base, a lever having conducting bifurcations fulcrumed on said member, conducting members between which said lever is adapted to oscillate to connect them electrically with said member, a resistance device, conducting devices fixed to said base and clamping the ends of said resistance device, and means comprising a conducting device concealed in said base for connecting one of said conducting devices 100 with one of said conducting members, whereby said resistance is cut in and out of circuit through said lever.

10. In a switching mechanism, the combination with a base, of a conducting member fixed to said base, a lever having conducting bifurcations fulcrumed on said member to oscillate parallel with said base, a pair of conducting members fixed to said base with which said lever is adapted to 110 make contact alternately, a second conducting lever, a conducting member fixed to said base on which said second lever is fulcrumed to oscillate parallel with said base, a conducting member fixed to said base and 115 adapted to be engaged and disengaged by said second lever, a resistance device, conducting devices clamping the ends of said resistance device and fixing it to said base, and conducting means connecting said conducting devices with conducting members aforesaid, whereby said resistance is adapted to be thrown in circuit through said lever first named when engaging one of said pair of conducting members.

11. In a switching mechanism, the combination with a base, of a conducting member fixed thereto, a lever having conducting bifurcations fulcrumed on said member so 120 as to oscillate parallel to said base, a con-

ducting member fixed to said base and with which said lever is adapted to make and break contact, a resistance device, conducting devices for clamping said resistance device and fixing it to said base, and means for connecting one of said clamping devices with said conducting member second named.

12. In a switching mechanism, the combination with a contact, of a lever adapted for engaging said contact, a spring pressed 10 detent carried by said lever, and a segment with which said lever is connected so as to prevent its movement transversely to its plane of oscillation and with which said

detent is adapted to be connected so as to 15 prevent the oscillatory movement of said lever.

13. In a switch mechanism, the combination with a base, of a contact fixed to said base, a lever fulcrumed on said base so as 20 to oscillate parallel thereto for engaging and disengaging said contact, and a segment with which said lever is connected so as to control the movement of the latter transversely to its plane of oscillation.

In testimony whereof I have hereunto set my name this 18th day of November, 1918.

WALTER S. MAYER.
